(57) **CLAIM**

The ornamental design for a display device with graphical user interface having a progress indicator animation, as shown and described.

DESCRIPTION

FIG. 1 is a front view of a first image of a display device with graphical user interface having a progress indicator animation according to the invention.

FIG. 2 is a second image thereof.

FIG. 3 is a third image thereof.

FIG. 4 is a fourth image thereof.

FIG. 5 is a fifth image thereof.

FIG. 6 is a sixth image thereof.

FIG. 7 is a seventh image thereof.

FIG. 8 is an eighth image thereof.

FIG. 9 is a ninth image thereof.

FIG. 10 is a tenth image thereof.

FIG. 11 is an eleventh image thereof.

FIG. 12 is a twelfth image thereof.

FIG. 13 is a thirteenth image thereof; and,

FIG. 14 is a fourteenth image thereof.

The appearance of the transitional image sequentially transitions between the images shown in FIGS. 1, 2, 3, 4, 5, 6,

(Continued)

7, 8, 9, 10, 11, 12, 13, and 14. The progress period in which one image transitions to another image forms no part of the claimed design.

The broken lines, showing of the electronic device and display screen are for the purpose of illustrating environment and forms no part of the claimed design. The broken line showing of elements, including the icon in the middle of the circle on FIGS. 10-17, on the display screen forms no part of the claimed design.

The appearance of FIGS. 1, 2, 3, 4, 5, 6, 7, 8, 9, 10, 11, 12, 13, and 14 using black is to show color contrast with the white section.

1 Claim, 8 Drawing Sheets
